CLAIM

The ornamental design for corner ladder stabilizer, as shown and described.

DESCRIPTION

FIG. 1 is a perspective view of a corner ladder stabilizer, the broken lines showing a building corner and a ladder are for illustrative purposes only and form no part of the claimed design;

FIG. 2 is a top plan view;

FIG. 3 is a back view;

FIG. 4 is a left side view, the right side being identical;

FIG. 5 is a front view;

FIG. 6 is a sectional view taken along lines 6—6 of FIG. 2;

FIG. 7 is an enlarged end view of the foot member; and,

FIG. 8 is an enlarged fragmentary side view thereof.
